UNITED STATES PATENT OFFICE.

JOSEPH L. CHEROT, OF ST. LOUIS, MISSOURI, ASSIGNOR OF ONE-HALF TO
LILBURN G. MCNAIR, OF SAME PLACE.

SHUTTER-FASTENER.

SPECIFICATION forming part of Letters Patent No. 416,992, dated December 10, 1889.

Application filed October 2, 1889. Serial No. 325,760. (No model.)

To all whom it may concern:

Be it known that I, JOSEPH L. CHEROT, a citizen of the United States, residing at the city of St. Louis, State of Missouri, have invented a certain new and useful Improvement in Locks or Holdfasts for Window-Shutters, of which the following is a full, clear, and exact description.

My invention relates to that class of devices for securing the ordinary lever-catches or fastenings of outside window-shutters when closed in the fastened position, the object of which is to prevent the unfastening of the catches from the outside of the window.

It consists of an arm or lever, which is fulcrumed to the window-sill and coupled, by means of a link-yoke or equivalent device, to the lever-catch of a window-shutter, when closed and fastened in the ordinary manner, the free end of the arm or lever being located in the path of the window-sash, so that on closing the latter the arm or lever is thereby operated to firmly hold the shutter-catch in the fastened position and prevent its being raised or unfastened from the outside of the window.

On the accompanying drawings, Figure 1 represents a transverse section through the lower parts of a window shutter or sash, the shutter being closed against the window-sill and fastened by an ordinary lever-catch with my invention applied thereto, and Fig. 2 a sectional plan thereof taken on the line 2 2 in Fig. 1.

Like letters of reference denote like parts in both figures.

a represents the lower portion of an outside window-shutter in its closed position against the window-sill *b*, to which it is fastened by an ordinary lever-catch *c*. Behind and centrally in line with the catch *c* a preferably forked arm or lever *d*, having its forked ends adjacent to the catch *c* fulcrumed at *e* to the window-sill *b*, while its free and connected end portion, which is preferably flattened, extends across the path of the window-sash *f*, and is normally held at a slight upward inclination from the fulcrum *e*, as seen in dotted lines, Fig. 1, by a link or yoke *g*, which is coupled at its forked ends to the forked portions of the arm or lever *d* at a suitable distance from the fulcrum *e*, the

other looped end of the yoke *g*, when the shutter *a* is closed and fastened, as shown, being passed over and held by the inner curved edge of the shutter-catch *c*.

In operation, on closing the window-sash *f* its lower edge descends upon the free end portion of the forked arm or lever *d*, which is thereby depressed radially to its fulcrum *e* into the position shown by full lines in Fig. 1, thereby causing the link or yoke *g* to constrain downward and firmly hold the shutter-catch *c* in the "fastened" position, so that it cannot be raised or unfastened from the outside of the window, nor until the sash *f* is raised from the inside of the window for releasing the arm or lever *d*, which, owing to the tension of the parts induced by its previous depression, then springs back to its normal position. When required to unfasten the shutter *a*, the arm or lever *d* is thrown upward on its fulcrum *e* and the yoke *g* unhitched from the shutter-catch *c*.

For preventing the withdrawal endwise of the arm or lever *d* from its position beneath the closed sash *f* on the removal of the fulcrum *e*, the free end of the arm or lever *d* may be formed with an upwardly-projecting lug or flange *h*, which sets against the inside of the sash *f*.

I claim as my invention—

1. In a window-shutter fastening, the combination of an arm or lever fulcrumed to the window-sill and extending across the path of the window-sash, the said arm or lever being coupled by a link or yoke to the shutter catch or fastening, substantially as shown, and for the purpose described.

2. In a window-shutter fastening, the combination of an arm or lever fulcrumed to the window-sill and extending across the path of the window-sash, the said arm or lever being coupled by a link or yoke to the shutter catch or fastening and provided at its free end with a lug or flange, substantially as shown, and for the purpose described.

In testimony whereof I have affixed my signature, in presence of two witnesses, this 18th day of September, 1889.

JOSEPH L. CHEROT.

Witnesses:

PAUL BAKEWELL,
J. W. CROOKES.
